US00D774465S

(12) **United States Design Patent** (10) **Patent No.:** **US D774,465 S**
(45) **Date of Patent:** **** Dec. 20, 2016**

(54) **MALE ELECTRICAL CONNECTOR**

(71) Applicant: **DSM&T Company, Inc.**, Fontana, CA (US)

(72) Inventor: **Sergio Corona**, Upland, CA (US)

(73) Assignee: **DSM&T Company, Inc.**, Fontana, CA (US)

(**) Term: **15 Years**

(21) Appl. No.: **29/554,988**

(22) Filed: **Feb. 17, 2016**

(51) LOC (10) Cl. **13-03**

(52) U.S. Cl.

(57) **CLAIM**

The ornamental design for a male electrical connector, as shown and described.

DESCRIPTION

FIG. 1 is a top, front, right side perspective view of my new design of a male electrical connector.

FIG. 2 is a right side elevational view thereof.

FIG. 3 is a left side elevational thereof.

FIG. 4 is a top plan view thereof.

FIG. 5 is a bottom plan view thereof.

FIG. 6 is a front side elevational view thereof; and,

FIG. 7 is a rear side elevational view thereof.

The broken lines in FIG. 7 are included to show environmental structure and form no part of the claimed design.

1 Claim, 2 Drawing Sheets
